[57] CLAIM

The ornamental design for a plumbing fitting handle, as shown and described.

DESCRIPTION

FIG. 1 is a top perspective view of a plumbing fitting handle showing my new design;

FIG. 2 is a front elevational view thereof;

FIG. 3 is a left side elevational view thereof;

FIG. 4 is a right side elevational view thereof;

FIG. 5 is a top plan view thereof; and

FIG. 6 is a bottom plan view thereof.

The fragmentary broken line representations of a toilet tank wall in FIG. 1, and of a toilet trip lever control stem in FIGS. 3-6 are for purposes of illustration only.

FIG. 1

FIG. 2

FIG. 3

FIG. 5

FIG. 4

FIG. 6
